UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,240,234.

Specification of Letters Patent. Patented Sept. 18, 1917.

Application filed February 10, 1913. Serial No. 747,349.

To all whom it may concern:

Be it known that I, HAAKON A. MARTIN, a citizen of the United States, residing at Dayton, in the county of Montgomery and

5 State of Ohio, have invented certain new and useful Improvements in Cash-Registers, of which I declare the following to be a full, clear, and exact description.

This invention relates to cash registers and among its main objects is the provision of a differential mechanism which shall operate with as little jar and strain to the machine as possible. Certain well known registering machines are arranged to 10 connect the differential elements from their actuating devices at different points of the strokes of the latter through the employment of keys or the like. Such constructions cause some jar to the mechanism when the disconnection takes place. In the present construction, devices are provided whereby elements are given a constant extent of movement and a differential movement obtained therefrom by varying the pivotal 15 points. Thus the entire constant stroke of the element may be employed and no danger of disconnection is found.

Another object of the invention is to provide a novel means for arresting keys to prevent simultaneous depression of keys in the same bank and also for locking a depressed key in depressed position during an operation of the machine and otherwise preventing manipulation of keys during an operation.

35 With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Of said drawings:—

45 Figure 1 is a transverse vertical section of a cash register with the casing omitted showing the differential mechanism and its connections to the driving mechanism and the accounting devices.

50 Fig. 2 is a sectional view of one of the banks of keys showing the manner in which the keys operate fulcruming plungers for the differential mechanism.

Fig. 3 is an enlarged side elevation of

one of the banks of keys showing the key 55 detents and key arresters and locking devices.

Fig. 4 is an enlarged detail of the totalizer and its actuating mechanism.

Fig. 5 is a detail of a cam for operating certain indicator alining devices. 60

In the present invention the differential mechanism is given positively an even motion requiring the same time for operation, no matter what the amount is to be added. As before noted, certain registering mechanisms already known provide for disconnecting the differential elements from their operating devices at varying parts of the stroke of the latter. Thus the differential element is moved at a constant speed through 70 whatever extent of movement is given it and is suddenly stopped at the end of that movement. In the present case a constant number of degrees of rotation of the main operating shaft are employed, no matter 75 what the number to be added and thus movement of the parts is more even and the machine is not jarred.

The register shown in the drawings includes a plurality of banks of keys each 80 bank of which is constructed to control one denominational section of the operating mechanism. The operating mechanism consists of levers and segment gears having 85 connections to control certain indicator setting mechanism and for driving a totalizing device. The driving mechanism has connections for rocking one end of said levers an invariable extent. The other ends of said 90 levers are pivoted to the segments and ordinarily when no keys are depressed, idly rock around the latter's pivots. The keys have connections for fulcruming said levers at different points intermediate their ends, consequently when keys are depressed the levers 95 rock around their key fulcrums and thereby drive the segment gears to which they are pivoted at their upper ends. In this manner the segment gears receive differential movement and communicate the same to the 100 indicator setting mechanism and to the totalizing device.

The keyboard consists of a plurality of banks of keys, each bank being provided with a key detent having connections to 105 operate a key arresting and locking device whereby when any key is depressed, a detent will be shifted and thereby move the

arresting and locking device to operative position, said device operating to permit the depression of only one key in a bank.

The indicator setting mechanism is novel 5 in the present case and specifically only, and a form of device for effecting transfers in the totalizer substantially similar to that shown, is found in the prior art.

The main drive shaft 1 of the machine is 10 shown in section in Fig. 1, and this shaft, as is usual in cash registers, is caused to make one rotation at each operation of the machine by any driving mechanism such as a motor, not shown in the present drawings.

15 For the purpose of driving the differential mechanism the shaft 1 carries fast a cam 2 having a groove 3 cut therein for operating on a roller 4 pivoted on a pitman 5. The pitman is forked over shaft 1 at its rear end 20 to be supported by the shaft, and at its forward end is pivoted by a pin 6 to an arm 7 fast to a rock shaft 8 journaled in the side frames 9. Fast to shaft 8 are a plurality of arms 10, one for each bank of keys, and 25 the rear ends of which are each connected through a link 11 with differential lever members 12. The levers 12 are connected at their upper ends to segment gears 13 by pins 14 passing through slots 15 in the segment gears 13 which constantly mesh with the rack teeth on the upper end of the levers 43 which are loosely mounted on a transverse shaft 44. The gears are loosely journaled at their upper ends on pins 16 carried 35 by key supporting frames 17.

With this construction the rotation of shaft 1 causes first a forward movement of pitman 5 and then a return to its normal position, as shown in the drawing. On the 40 forward movement of the pitman, shaft 8 is rocked, and thus through arms 10 pushes the links 11 upwardly, thereby rocking the levers 12 a certain angular extent upwardly around their pivots 14 to segment gears 13, 45 provided no key is depressed. If keys are depressed the levers will be fulcrumed at points intermediate their pivotal connection with links 11 and segment gears 13, consequently on operation of pitman 5 the levers 50 12 will rock around the key controlled pivots and thereby differentially drive segment gears 13. The latter have connections for driving the accounting device and controlling the indicator setting mechanism, as described farther on.

Each bank of keys consists of a plurality of keys 18 slidably mounted in the frames 17 supported by the side frames 9. The keys are compressible against the action of springs 60 19 compressed between lugs 20 on the keys and flanges 21 of the key frames, and each key is provided with a slot 22 surrounding a pin 23 on a plunger 24, also slidably mounted in the key frame but to move transversely of the direction of movement of the

key, consequently slot 22 is inclined to the direction of movement of the key in order to force the plunger 24 to the right as shown in Fig. 2. Such movement of one of the plungers causes it to pass through a slot 25 70 in a key arresting device 26. The plunger also passes through one of the pivot holes 27 in the lever 12 for the corresponding bank. The outer end of the plunger enters a plate 28 fastened to the side of key frame 75 17, as shown in Figs. 1 and 2, and is thus supported by this plate and the key frame 17 during the operation of the machine when the lever 12 is rocked around the plunger. It will be seen that the levers 12 move between the key frame 17 and the plate 28 and are thus guided to move properly.

Each key is provided with a laterally extending lug 29 for coöperating with one of the inclined edges 30 of a key detent 31. 80 The detent 31 is supported by pins 32 on the key frame 17 passing through slots 33 in the detent, thus permitting a sliding movement of the detent in the direction of its length. The inclines 30 are differentially disposed 90 with respect to lugs 29 and consequently the detent is forced upwardly differentially with respect to the keys, the uppermost or "1" key moving the detent nine times as far as the lowest or "9" key moves it. At the lower 95 ends of inclines 30 are notches 34 serving to retain the depressed keys in their inner positions by a slight return movement of the detent when the depressed key arrives at its inner position. This return movement is accomplished by springs 35 which normally 100 serve to retain the detents and members 26 operated thereby in the position shown in Fig. 3.

Each detent is pivoted at its lower end to 105 a lever 37 pivoted to the corresponding key frame by the pin 38 and having at its lower end a slot 39 encircling a pin 40 on one of the arresting members 26, and the members 26 are provided with slots 41 through which 110 pass fixed pins 42 on the key frames. When a key is depressed a corresponding plunger 24 is projected through the slot 25 in the member 26. Simultaneously the key detent 31 is moved upwardly to an extent depending 115 upon the particular key employed. Thus the plunger 24 constitutes a pivot around which the arresting member 26 may rock, as its movement is limited by the pin 42. The upward movement of the arresting 120 plate 26 serves to rock the lever 37 differentially in a clockwise direction. Thus its slot 39 moves more or less past the pin 40 in the arresting member 26. The movement of this lever 37 would, in the absence of pin 125 42, carry the arresting member 26 in a downward direction, or to the left as shown in Fig. 3. However, the presence of pin 42 prevents this movement and therefore the passing of slot 39 more or less past the pin 130

40 compels the arresting plate 26 to move in a counter-clockwise direction around the projected plunger 24 as the center. Thus the end of the member 26 surrounding pin 5 42 moves downward, as this is the direction of inclination of slot 39. The two sides of the arresting member 26 therefore pass in front of plungers on all the other keys except that depressed and prevent the depression of any of them, whereby only one key in the bank may be depressed at a time. The object of having a differential movement to the key detent 31 is to give substantially a uniform extent of rocking movement of the 10 plate 26. The plungers 24 are at different distances from the pin 42 and therefore would cause different extents of rotation of the plate 26, but the difference of distance of the plungers from the pin 42 is compensated for by the different extents of movement given the key detent plate 31.

The totalizer and its actuating devices are best shown in Fig. 4 and a brief description of these parts may next be given.

25 It has been explained how the levers 43 are given a differential movement depending upon the keys depressed. Each of these levers carries at its lower end a rack segment 465 carried on the lever 43 by pins 491 fast on the lever and projecting through curved slots 492 in the racks. Each lever 43 in addition to the segment rack 465 carries a tripping plate 473, these plates also being carried on pins 491 which pass through slots 35 493 in the tripping plates. Loose on the shaft 8 is a series of arms 471, the outer ends of which are normally engaged against these tripping plates 473. Each of the totalizer elements is provided with a pin 472 which, as the element passes from its "nine" to zero position, engages the projection of the corresponding arm 471 and rocks this arm slightly, thereby forcing the tripping plate 473 toward the shaft 44 around which 45 lever 43 rotates. A latching plate 474 is carried on each lever 43, drawn by a spring as shown, so that a flange 493 thereon rests normally against the inner edge of tripping plate 473. An extension of the latching arm 50 474 is provided with a flange 494 normally engaging in a notch in the segment rack 465. A lever 466 is also pivoted to the lever 43 and is normally drawn by a spring 467, thus tending to move the segment rack 465 through the distance between any two of its teeth.

When a totalizer wheel 46 passes from "nine" to zero its pin 472 engages the projection on arm 471 thereby moving the tripping plate 473 toward the shaft 44. As the flange 493 of the latching pawl 474 is in engagement with this tripping plate 473, this latching arm is also moved and this flange 494 releases the rack segment 465, whereupon the spring 467 moves the rack enough

to carry the totalizer element of next higher order an additional step, thus completing or turning in the transfer.

To engage and disengage the totalizer elements with the segment racks, they are carried on a rod 461 supported by two frame arms 462 carried by collars on the shaft 8. To one of these collars an arm 464 is rigidly held and this arm is connected to a pitman 465 which is provided with a roller 466 riding in the cam groove 467 of a box cam 468. It will be seen from Fig. 4 that the shape of this cam is such as to retain the totalizer out of engagement with the rack segments during the setting stroke thereof, and to maintain it in engagement with these segments during their return stroke. Thus the totalizer elements, as is requisite, will move in one direction only.

It is necessary to reset the rack segments 465 after each transfer, and to this end a bar 482 is carried by frame arm 481 fast on a rod 483. One of these frame arms is extended upwardly from the rod and connected to a pitman 484 which carries roller 485 riding in the second cam groove 486 in the disk 468. The shape of this cam groove is such as to engage the bar 482 with any of the rack segments 465 which have been given a transfer movement and reset them against the tension of springs 467 substantially at the end of each operation of the machine. When the racks are so reset, the latching pawls 474 again engage the rack segments and retain them until another transfer is necessary.

The connections for setting the indicators and type carriers are operated by segment gears 13. The latter have forwardly extending arms 47 to which are pivoted by pins 48 beams 49 connecting the segment gears 13 with links 50 which are pivoted by pins 53 to the rear ends of the beams 49. The links 50 are pivoted at their lower ends to arms 51 fast on shafts 52. These shafts may have 110 connections for setting type carriers, as is known in the art. The pivots 53 connecting links 50 with beams 49 also connect the beams to segment gears 54 journaled on the pivot pins 16 and meshing with pinions 55 115 fast to indicator drums 56. The pins 53 ride in slots in the gears 54.

When the beams 49 are rocked differentially around their pivots 53 by movement of segment gears 13 the segment gears 54 are 12 locked against movement by alining pawls 57 fast to a rock shaft 58 operated by a cam 581 on shaft 1 and having connections to rock shaft 58 through a pitman 59, a bell crank lever 60 pivoted on a rod 61, and a 125 link 62 connecting the bell crank lever with an arm 63 fast to shaft 58. As the beams 49 are rocked around pivot pins 53 the rollers 64 carried centrally by said beams are differentially positioned with respect to V- 130

shaped cams 65 fast to a rock shaft 66. The shaft 66 has fast thereto a crank arm 70 connected to a pitman 71. This pitman carries a roller 74 which rides in the groove 73 of a cam disk 72. The shape of this groove is such that the pitman is carried up and then restored at each operation of the machine. This upward movement of the pitman causes a forward movement of the cams 10 65 and thus engages some time during the operation with the rollers 64 and restores them to their normal central position. At this time the ends 48 of the beams 49 are held rigidly set and consequently the other 15 ends of the beams are compelled to rock, thus positioning the indicators and the printing devices. It will be understood that during this movement the alining devices 57 are withdrawn from the indicator operating 20 segments by the mechanism described. After the indicators are set the alining devices are returned to their locking position and remain thus until the succeeding operation of the machine, whereby the indicators are 25 locked against accidental movement.

To enter a transaction it is necessary to depress the keys 18 corresponding in value to the amount of the transaction, and then to cause a single rotation of shaft 1 in a 30 clockwise direction as viewed in Fig. 1. The depression of the keys effects the shifting of the corresponding plungers 24 through the holes 27 in the differential levers 12. The key by shifting detent 31 upwardly also 35 rocks the corresponding lever 37 clockwise around its pivot 38 and thereby positions the member 26 in front of the unmoved plungers 24 and in this manner prevents manipulation of keys during the operation 40 of the machine. Then upon the rotation of drive shaft 1 pitman 5 is first moved forwardly, thus through arms 7, 10, and links 11 rocking the levers 12 clockwise around the operated plungers 24, and as the plungers 45 are differentially located along the length of the levers, any desired differential movement is imparted to the upper ends of the latter. The pins 14 on the levers by engagement with segment gears 13 at the slots 50 15 differentially rock the segment gears and through them differentially rocking segment gears 43 which carry the actuators for the totalizer and also differentially rocking beams 49 around their pivots 53. Continued 55 rotation of drive shaft 1 results in the operation of cams 65 and thereby the differential positioning of the indicators and the type carriers. Toward the end of rotation of drive shaft 1 the detents 31 and locking 60 members 26 are restored to normal position by a restoring device suitably constructed to lift detents 31, but not shown.

From the foregoing description it will be seen that the present invention provides an

extremely simple and positively operated 65 differential mechanism.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow. 75

What is claimed is:

1. In a machine of the class described, the combination with accounting mechanism, of actuating mechanism therefor including a segment gear having a slot, a lever 80 having a pin extending into said slot, means for pivoting said lever at any one of a plurality of different points, and means connected to said lever to rock it around a determined one of said points. 85

2. In a machine of the class described, the combination with a bank of keys, of a key 90 detent plate moved by said keys and serving to retain any key in depressed position, plungers one for and moved by each key, 95 and a plate adjusted by said detent plate into the paths of the plungers of all the undepressed keys.

3. In a machine of the class described, the combination with a bank of keys, of a key 95 detent plate having inclined edges engaged and moved by the keys and serving to retain any key in depressed position, plungers one for and moved by each key, and a plate adjusted by said detent plate into the paths 100 of the plungers of the undepressed keys.

4. In a machine of the class described, the combination with a bank of keys and a supporting key frame, of a key detent plate carried by the key frame, and moved by any key, plungers moved by each of said keys, and a second plate carried by said key frame and moved by said detent plate into the paths of the plungers of the undepressed keys. 110

5. In a machine of the class described, the combination with a bank of keys, and a key 115 detent plate moved by any key of the bank, of plungers moved by the keys, a second plate adjacent said plungers and through which the moved plungers project to serve as pivots therefor, and connections whereby said key detent plate rotates said second plate around the plunger of the depressed key and thereby into the paths of plungers 120 of the undepressed keys.

6. In a machine of the class described, the combination with an actuating lever, of a bank of depressible keys, elements arranged at equal distances along the length of the lever, normally disconnected therefrom and positively moved by said keys into positions to form fulcrums for said lever, and an ac- 125

counting mechanism controlled by said actuating lever.

7. In a machine of the class described, the combination with an accounting device, of an actuating lever for controlling said accounting device, means for moving one end of said lever through a path of invariable extent, a bank of keys each provided with a cam slot, and elements provided with pins engaging in the slots of their respective keys so that upon movement of any one of said keys a corresponding element will be moved into position to form a fulcrum for said actuating lever.

15 8. In a machine of the class described, the combination with an accounting mechanism, of an actuating lever controlling the same, a bank of depressible keys each provided with a slot, and elements arranged at equal distances along the length of said lever normally disconnected therefrom and provided with pins engaging the slots of their corresponding keys so that upon depression of any one of said keys the corresponding element is moved at right angles thereto to cause the element to form a fulcrum for said actuating lever, the slot and pin connection being so constructed that upon movement of the key to normal position the element will be moved with it to normal position.

9. In a machine of the class described, the combination with a differentially movable member, of an oscillatory element connected thereto, a series of keys controlling the extent of movement of said differentially movable member, and plungers controlled by said keys to fulcrum said element at different points along its length so that the dif-

ferential movement of said member will oscillate the element to a uniform extent.

10. In a machine of the class described, the combination with a bank of keys, of a key detent plate moved by said keys and serving to retain any key in depressed position, plungers one for and moved by each key, a plate adjusted by said detent plate about the operated plunger into the paths of the plungers for all the undepressed keys, a lever, and means for moving one end of said lever through a path of invariable extent, said plungers being moved into position to vary the extent of movement of the other end of said lever.

11. In a machine of the class described, the combination with a bank of keys, of a key detent plate, having inclined edges engaged and moved differentially by the keys, and serving to retain any key in depressed position, plungers one for and moved by each key, a member adjusted by said detent plate and coöperating with said plungers so that the member is rocked to a uniform extent about any operated plunger into the paths of the plungers of the undepressed keys, a lever, and means for moving one end of said lever through a path of invariable extent, said plungers being moved into position to vary the extent of movement of the other end of the lever.

In testimony whereof I affix my signature in the presence of two witnesses.

HAAKON A. MARTIN.
